UNITED STATES PATENT OFFICE.

ALBERT COLEY AND ARTHUR W. MARLER, OF SAPULPA, OKLAHOMA.

ADVERTISEMENT DISTRIBUTOR.

1,417,500.

Specification of Letters Patent. Patented May 30, 1922.

Application filed June 23, 1920. Serial No. 391,251.

To all whom it may concern:

Be it known that we, ALBERT COLEY, and ARTHUR W. MARLER, citizens of the United States, residing at Sapulpa, in the county of Creek and State of Oklahoma, have invented certain new and useful Improvements in Advertisement Distributors, of which the following is a specification, reference being had therein to the accompanying drawing.

10 The present invention relates to an aeroplane attachment, and more particularly to a device for distributing advertising matter such as bills, pamphlets, catalogues, messages, and samples of various articles from 15 an aeroplane.

The principal object resides in providing a carrier positioned upon the aeroplane in easy reach of the pilot so that he may release the parts so as to drop the advertising matter at will.

Another object consists in providing the carrier with a plurality of compartments containing the advertising matter, and means for releasing the matter in the various 25 compartments separately or in unison.

A further object resides in providing means for forcing the advertising matter from the carrier so that it will drop free of the aeroplane and not hinder the operation 30 of the machine.

With these and other objects in view our invention consists in the novel details of construction and arrangement of parts which will be more clearly understood from the 35 following specification and drawings, in which:—

Figure 1 is a top plan,

Figure 2 is a front elevation,

Figure 3, is a fragmental vertical section 40 through two of the barrels with portions of the supporting frame shown in elevation, and

Figure 4 is a detailed perspective of the operating crank shaft and rods.

45 In carrying out the invention we provide a carrier which may be connected to the aeroplane in any desired manner but will be so positioned as to be within easy reach of the operator. The carrier is formed with 50 supporting legs 1 connected at the top by a handle 2. A top board 3 extends between and is secured to the legs 1, and is provided with a plurality of openings for a purpose to be later described. A second board 4 is 55 secured to the legs 1 in spaced relation to the top board 3 and this board is also pro-

vided with a plurality of openings through which barrels 5 pass. These barrels are secured at their upper ends to the under side of the top board 3 and the upper end of each barrel surrounds one of the openings formed in the board 3. A door 6 is hingedly connected to the lower end of each barrel and is held in closed position by a catch 7 which is pivoted to the barrel at 8. As shown, the catch is formed with a right angle extension on each end, the upper extension passing through an opening adjacent the lower end of the barrel, for a purpose to be later described, and the lower extension engaging 70 under the edge of the door to hold it in closed position.

A follower 9 is slidably mounted in each barrel and has a rod or bar 10 connected to the upper face thereof. The bars 10 are 75 adapted to pass through the openings formed in the top board 3. A hook 11 is formed on or secured to the upper end of each of the rods or bars 10 and these hooks are used for raising the followers in a manner to be later 80 described. A notch 13 is formed in one edge of each of the bars or rods 10 to be engaged by a catch to be later described.

A coil spring 14 surrounds each of the rods or bars 10 between the under side of 85 the top board 3 and the upper surface of the follower 9. These coil springs will normally tend to force the followers towards the lower ends of the barrels.

A flat bar 15 is secured to one edge of each 90 of the followers 9 and extends longitudinally of the barrel 5. The lower end of the bars 15 are curved as indicated at 16 so as to fit around the upper right angled extension of the catch 7. The lower end of the bar 15 engages the barrel as indicated at 17. A flat bar 18 is secured to the opposite edge of the follower 9 and the lower end is curved as shown at 19 to engage the side of the barrel. The curved portion 16 of the bar 15 will engage and disconnect the catch 7 when the follower 9 is depressed and the end 17 of this bar 15, as well as the end 19 of the bar 18, will prevent the advertising matter from sticking to the interior of the barrel. In the 100 drawings we have illustrated the bar 18 as of less length than the bar 15, but it will be understood that the bars might be made of various lengths without departing from the spirit of the invention. A plurality of bell 110 crank levers 20 are pivotally connected, at 21, to the upper surface of the top board 3

and, as shown, one of these levers will be adjacent each of the rods or bars 10 and will be adapted, when the bars are raised, to engage in the notches 13, as shown. A coil spring 22 is connected to each of the bell crank levers, and to the board 3, and tends to normally engage the end of the lever in the notch 13. A rod 23 is secured to each of the bell crank levers 20 and extends towards the front edge of the board 3 so as to be in easy reach of the operator of the aeroplane. The outer end of each of these rods is bent at right angles to form an extension 24.

A crank shaft 25 is adapted to be secured to the carrier by means of staples 26, or other suitable fastening means, and the offset portions 27, of the shaft, are adapted to be positioned to engage under the right angled extensions 24 of the rods 23. A hand lever 28 is formed on, or secured to, the shaft 25, for rotating the same, when desired, in its bearings.

From the foregoing detailed description, it is thought that the construction of our device will be clearly understood. As stated in the objects of the invention, the carrier is adapted for distributing advertising matter from an aeroplane, and will be made of some light material which will not add unnecessary weight to the aeroplane. As previously stated, the carrier may be secured to the aeroplane in any suitable manner, and while we have illustrated twelve separate drums for holding and distributing the advertising matter, it will be understood that any number of drums might be used without departing from the spirit of the invention.

When it is desired to fill the barrels, the hooks 11, of the bars or rods 10, are engaged and the followers 9 raised in the barrels, against the tension of the coil springs 14. When the notch 13 reaches the proper position the end of the bell crank lever 20 will be forced therein through action of the coil spring 22. These bell crank levers will hold the followers in raised position and the advertising matter may be inserted through the opening formed in the lower end of the barrel. It will be understood that the door 6 will be opened to allow the insertion of the matter. After the advertising matter has been placed in the barrel the door 6 will be raised and held in closed position by means of the catch 7. If desired a jack or other suitable lifting device might be inserted beneath the hooks 11 for raising the followers.

To release the matter from the barrels, it is necessary to operate the rods 23 connected to the bell crank levers 20. If it is desired to operate all of the barrels in unison the handle 28 of the shaft 25 will be grasped and the shaft rotated. The offset portions 27, engaging the right angled extensions 24,

will pull the rods 23 and thereby release the bell crank levers 20 from the notches 13 and allow the coil springs 14 to press the followers 9 towards the lower ends of the drums. The downward movement of the followers will lower the bars 15 and the curved portions 16 will release the catches 7 to allow the doors 6 to open. The ends 17 and 19, of the bars 15 and 18, respectively, will scrape the sides of the drum and prevent the advertising matter from sticking in the drum. If it is desired to discharge the matter from the drums separately any one of the rods 23 might be operated and in turn operate the bell crank lever associated therewith.

While we have described the preferred form of our invention, it will be understood that minor changes in the details of construction and operation might be made without departing from the spirit of the invention.

Having fully described our invention, what we claim as new and desire to secure by Letters Patent is:—

1. An advertisement distributor comprising a barrel, a door hinged to the lower end of the barrel, means for holding the door closed, a plunger operable in the barrel, scrapers carried by the plunger and engaging the inner wall of the barrel, and means for releasing the door.

2. An advertisement distributor comprising a barrel, a door hinged to the lower end of the barrel, a catch pivotally connected to the barrel and adapted to hold the door in closed position, a right angled extension formed on the catch and extending into the barrel, a plunger operable in the barrel, and a bar connected to the plunger and adapted to engage the right angled extension of the catch for disengaging the catch from the door, said bar having a recess intermediate its ends to normally receive the right angled extension.

3. An advertisement distributor comprising a barrel, a door hinged to the lower end of the barrel, a catch for holding the door closed, a plunger operable in the barrel, and means carried by the plunger for releasing the catch.

4. An advertisement distributor comprising a barrel, a door hinged to the lower end of the barrel, a catch connected to the barrel and adapted to hold the door in closed position, a plunger operable in the barrel, and a bar carried by the plunger for engaging and releasing the catch.

5. An advertisement distributor comprising a barrel, a door hinged to the lower end of the barrel, a catch pivoted to the barrel and adapted to engage the door for holding it in closed position, a right angled extension formed on the catch and extending into the barrel, a plunger operable in the barrel, and

means carried by the plunger, and engaging the right angled extension of the catch for releasing the catch from the door.

6. An advertisement distributor comprising a barrel, a door hinged to the lower end of the barrel, a catch pivotally connected to the barrel and adapted to hold the door in closed position, a right angled extension formed on the catch and extending into the barrel, a plunger operable in the barrel, and a bar connected to the plunger and engaging the right angled extension of the catch for disengaging the catch from the door.

7. An advertisement distributor comprising a frame, a plurality of barrels secured to the frame, a spring-controlled plunger operable in each barrel, a rod secured to each plunger and provided with a notch, a plurality of levers pivotally connected to the frame, one of said levers adapted to engage in the notch of each plunger rod for holding the plunger in raised position, and means for releasing the levers separately or in unison.

8. An advertisement distributor comprising a frame, a plurality of barrels secured to the frame, a spring-controlled plunger operable in each barrel, a rod secured to each plunger and provided with a notch, a plurality of levers pivotally connected to the frame, one of said levers adapted to engage in the notch of each plunger rod for holding the plunger in raised position, a rod connected to each lever, and means for operating the rods separately or in unison.

9. An advertisement distributor comprising

ing a frame, a plurality of barrels secured to the frame, a spring-controlled plunger operable in each barrel, a rod secured to each plunger and provided with a notch, a plurality of levers pivotally connected to the frame, one of said levers adapted to engage in the notch of each plunger rod for holding the plunger in raised position, a rod connected to each lever, means for operating the rod separately, and a crank shaft rotatably connected to the frame for operating the rods in unison.

10. An advertisement distributor comprising a frame, a plurality of barrels connected to the frame, a door hingedly connected to the lower end of each barrel, a catch pivotally connected to each barrel for holding the door in raised position, a spring-controlled plunger operable in each barrel, means carried by each plunger for releasing the catch, a rod secured to each plunger and provided with a notch, a plurality of levers pivotally connected to the frame and adapted to engage the notches for holding the plungers in raised position, and means for operating the levers separately or in unison.

In testimony whereof we hereunto affix our signatures in the presence of two witnesses.
